UNITED STATES PATENT OFFICE.

SULLIVAN ROME AND JOSEPH IARUSSI, OF HUDSON, OHIO.

RAIL-JOINT.

1,227,832.

Specification of Letters Patent. Patented May 29, 1917.

Application filed February 20, 1917. Serial No. 149,854.

To all whom it may concern:

Be it known that we, SULLIVAN ROME and JOSEPH IARUSSI, citizens of the United States, residing at Hudson, in the county 5 of Summit and State of Ohio, have invented certain new and useful Improvements in Rail-Joints, of which the following is a specification, reference being had to the accompanying drawings.

10 This invention relates to certain improvements in rail joints and it is an object of the invention to provide a novel and improved insert block or regulator adapted to be positioned between the meeting ends of rails, and 15 which when in applied position, serves to prevent creeping of the rails or breaking of the angle bars or fish plates.

It is also an object of the invention to provide novel and improved means whereby 20 a good surface is maintained at the joint so that "pounding" is substantially entirely eliminated and whereby the breaking of the rail ends is prevented.

The invention consists in the details of 25 construction and in the combination and arrangement of the several parts of our improved rail joint whereby certain important advantages are attained and the device is rendered simpler, less expensive and otherwise more convenient and advantageous for use, all as will be hereinafter more fully set forth.

The novel features of the invention will hereinafter be definitely claimed.

30 In order that our invention may be the better understood, we will now proceed to describe the same with reference to the accompanying drawings, wherein—

Figure 1 is a view partly in elevation and 40 partly in section illustrating a block or regulator constructed in accordance with our invention in applied position; and

Fig. 2 is a side elevational view of the meeting ends of rails with our improved 45 block or regulator applied, a fish plate or angle bar being omitted;

Fig. 3 is a view partly in elevation and partly in section illustrating a block or regulator constructed in accordance with a further embodiment of our invention; and 50

Fig. 4 is a view partly in elevation and partly in section illustrating a block or regulator constructed in accordance with a still further embodiment of our invention.

55 As disclosed in the accompanying draw-

ings, R—R denote the meeting ends of rails and with which coact in a conventional manner the fish plates or angle bars P.

As is well known, rails are laid according to temperature, as for example, with the 60 temperature of 18° above zero F. rails are laid five-sixteenths of an inch apart. With the rails separated to this extent it will be at once self-evident that there is nothing to prevent the rails from creeping and instead 65 of a space of five-sixteenths of an inch the space will increase to ten-sixteenths or even more at certain places, while in other places there will be no space at all between the meeting ends of the rails. With warmer 70 weather it will be self-evident that the rails will have a tendency to become very tight.

It is the purpose of our invention to employ the block or regulator B comprising the head 1 adapted to conform to the cross 75 sectional configuration of the tread portion or head of a rail, and said head affords the shoulders 2 adapted to rest upon the upper marginal portions of the plates P.

Depending from the head at the longitudinal center thereof is the shank 3. The thickness of the head 1 and shank 3 will depend upon conditions and it will be understood that upon lowering of the temperature or upon the raising thereof it is the 80 purpose to remove the blocks or regulators B and replace the same with blocks or regulators of either increased or decreased thicknesses.

In applying a block or regulator B it is 90 only necessary to drop the same between the meeting ends of rails as the shank 3 is of a length to prevent the accidental displacement of the block or regulator.

The minimum length of the shank 3 95 should be such as to have the same terminate below the webs of the meeting ends of the rails but, as disclosed in the accompanying drawings, said shank 3 is of such a length as to have a portion 4 extend below the base 100 of the rails, and said extension 4 has removably inserted therethrough a pin 5 or the like which is of such a length as to underlie the meeting ends of the rails and thereby afford a positive means to prevent the removal of the block or regulator B.

As herein disclosed, the member 5 is illustrated as a conventional cotter pin.

From the foregoing description, it is thought to be obvious that a rail joint con- 110

structed in accordance with our invention is of an extremely simple and comparatively inexpensive nature and is particularly well adapted for use by reason of the convenience and facility with which it may be assembled, and it will also be obvious that our invention is susceptible of some change and modification without material departure from the principles and spirit thereof and for this reason we do not wish to be understood as limiting ourselves to the precise arrangement and formation of the several parts herein shown in carrying out our invention in practice, except as hereinafter 15 claimed.

As is illustrated in the embodiment of our invention as disclosed by Fig. 3 of the accompanying drawings, it is to be noted that the shank 3^a of the block B' is of such 20 a length as to terminate above the bottom of the rail R and does not have any locking or retaining means coacting therewith. This form of block or regulator has been found in practice to operate with a maximum of facility in connection with a straight line or at a curve.

In the embodiment of our invention as disclosed in Fig. 4 the shank 3^b of the block or regulator B² is also of a length to terminate above the bottom of the rail R but is only of a width substantially equal to the thickness of the webs of the meeting ends of the rails. This form of block or regulator is only adapted to be used in connection with a straight line and by this particular construction it has been found that a material saving in material can be had.

We claim:

1. As a new article of manufacture, a 40 block adapted to be inserted between the

meeting ends of rails, and comprising a head conforming to the cross sectional configuration of the tread portions of the meeting ends of rails, a shank depending from said head and of a length to extend beyond the bases of the meeting ends of rails, and a member removably engaged with the free end portion of the shank and adapted to coact with the base portion of the meeting ends of rails to hold the block against removal. 45

2. As a new article of manufacture, a block adapted to be inserted between the meeting ends of rails and comprising a head conforming to the cross sectional configuration of the tread portion of the meeting ends of the rails, a shank depending from said head and of a length to extend adjacent the base portion of the rails, and means 55 coacting with the end portion of the shank to hold the block against removal. 60

3. As a new article of manufacture, a block adapted to be inserted between the meeting ends of rails, said block including a head portion conforming to the cross sectional configuration of the tread portions of the meeting ends of the rails, a shank depending from said head and of a length to extend adjacent the base portion of the rails, and means 65 coacting with the block for holding the same against removal. 70

In testimony whereof we hereunto affix our signatures in the presence of two witnesses.

SULLIVAN ROME.
JOSEPH IARUSSI.

Witnesses:

MAYME K. SULLIVAN,
H. A. SULLIVAN.
